FOREIGN PATENT DOCUMENTS

GB 248234 A 3/1926

Primary Examiner — Anhdao Doan(74) *Attorney, Agent, or Firm* — Popovich, Wiles & O'Connell, P.A.**CLAIM**

The ornamental design for a landscaping block, as shown and described.

DESCRIPTION

FIG. 1 is a perspective view of a landscaping block;

FIG. 2 is a top plan view thereof;

FIG. 3 is a bottom plan view thereof;

FIG. 4 is a front elevational view thereof;

FIG. 5 is a rear elevational view thereof;

FIG. 6 is a left side elevational view thereof; and,

FIG. 7 is a right side elevational view thereof.

The portions of the landscaping block shown in broken lines form no part of the claimed design.
